WOOD LATHE

Frederick S. Brennan, Evanston, Ill., assignor to Rockwell Manufacturing Company, Pittsburgh, Pa., a corporation of Pennsylvania

Application April 15, 1957, Serial No. 45,731

Term of patent 14 years

(Cl. D54—6)

Figure 1 is a perspective view of a wood lathe showing my new design; and

Figure 2 is a perspective view thereof taken from the opposite side of the wood lathe shown in Figure 1 with the tailstock moved inwardly from the position shown in Figure 1.

I claim:

The ornamental design for a wood lathe, as shown.
